UNITED STATES PATENT OFFICE

141,189

DESIGN FOR A COMBINATION CLOCK AND RADIO

Harry Lewy, Baltimore, Md.

Application January 19, 1945, Serial No. 117,507

Term of patent 7 years

(Cl. D56—4)

To all whom it may concern:

Be it known that I, Harry Lewy, a citizen of the United States of America, residing at Baltimore, in the county of Baltimore and State of Maryland, have invented a new, original, and ornamental Design for Combination Clock and Radio, of which the following is a specification, reference being had to the accompanying drawing, forming a part thereof.

In the drawing:

Figure 1 is a front elevational view of a com-

bination clock and radio embodying my new design.

Figure 2 is a top plan view of the same.

Figure 3 is a side elevational view of the same. The left side and rear portion of the design are plain and unornamented.

I claim:

The ornamental design for a combination clock and radio, as shown and described.

HARRY LEWY.
